UNITED STATES PATENT OFFICE

2,544,942

CHAIN LINK INTERSPERSING MACHINE

Clarence E. Vandenberg, Blue Island, Ill., assignor to International Harvester Company, a corporation of New Jersey

Application July 25, 1949, Serial No. 106,532

3 Claims. (Cl. 59—7)

1

This invention relates to a new and improved chain link interspersing machine.

Chain making machines are known in the art. It is common procedure to insert a continuous strip of steel stock to one side of a chain making machine and have completed linked chain emerge from the other side of the machine. The links of chain formed by these continuously running chain making machines are as a rule of a fixed standard size and shape. On many occasions it is necessary to employ special links in a chain of this type, creating a problem to obtain chain with desired special link. At the present time, it is common practice to manually break apart completed chain and insert special links in the whole chain as desired. This practice lacks economy.

It is therefore a principal object of this invention to provide means in an automatically operable chain making machine for inserting special links into the chain just prior to completion thereof without hindering the continuous formation and assembly of the regular links constituting the major portion of the completed chain.

An important object of this invention is the provision of means for temporarily halting the chain making operation, thereupon causing the insertion of a special link to be formed with the entire chain and immediately thereafter instituting resumption of the regular chain making machine operation.

Another important object of this invention is to provide electrical means for controlling the operation of a chain making machine and in co-operation therewith providing adjustable means for effecting the insertion of a special link into position in alignment with the chain being formed and actually assembling the special link simultaneously with the assembling of the chain as a whole.

A further important object of this invention is to supply an injecting machine for special chain link in synchronism with the fabrication of regular chain.

Another and further important object of this invention is the provision of means in an interval timing device for adjustably controlling the number of regular chain links between the incorporation of special links.

Another and still further important object of this invention is to provide a vertically movable toothed rack operable upon each stroke of the chain making machine to advance the rack one tooth, and control means to effect a stopping of

2

the feed of the chain stock after a predetermined number of links of chain have been formed, thereupon causing an insertion of a special link and a resumption of normal operation of the chain making machine.

Other and further important objects of this invention will become apparent from the disclosures in the following specification and accompanying drawings.

- 10 In the drawings:
Fig. 1 is a front elevational view of a chain making machine.
Fig. 2 is a side elevational view of the chain making machine of Fig. 1.
15 Fig. 3 is an enlarged side elevational view of a portion of the device of Fig. 2 and showing the special link inserting mechanism.
Fig. 4 is a front elevational view of the device of Fig. 3.
20 Fig. 5 is a sectional view taken on the line 5—5 of Fig. 3.
Fig. 6 is a top plan view of chain shown partially fabricated with the special link incorporated therein.
25 Fig. 7 shows an enlarged perspective view of a special chain link such as used in the operation of this device.
Fig. 8 is an elevational view of the electrical-mechanical control apparatus for effecting the insertion of special chain link.
30 As shown in the drawings:
The reference numeral 10 indicates generally a supporting structure or framework for a punch press or the like. The press includes floor engaging leg members 11 and upwardly extending frame parts 12 and 13 for carrying a cross shaft 14. The shaft 14 is rotatably driven by means of a large gear 15 having rotation imparted thereto from a relatively small spur gear 16. The
- 35 shaft 14 is equipped with a crank 17 adapted to receive a crank arm or pitman 18. The lower end of the pitman 18 is provided with a ball end 19 which engages a similarly shaped ball socket 20 in a press plunger 21 as best shown in Fig. 2.
40 The press plunger 21 is adapted to receive and hold a multiple stage chain forming die 22.
- 45 A source of metal strip stock such as steel is shown at 23 and is carried on a reel 24 mounted on a supporting standard 25. The narrow strip 50 of material 23 having a width corresponding to the width of the chain being fabricated is fed upwardly into the punch press through a feeding mechanism designated by the numeral 26. The feeding mechanism is similar to that shown 55 in the long expired patent to Parker 1,556,538.

A pivoted knife edge 27 attached to a slider mechanism 28 is oscillated, and in combination with a pawl 29 and ratchet wheel 30 having a stop pin 31 for cooperation with a lug 35 on the pivoted knife edge 27 causes intermittent feeding of the strip of stock. A crank 33 is mounted on the press shaft 14 and a link member 34 extends downwardly to attachment with a bell-crank 35 to effect reciprocal movement of the slider 28. Thus press operation permits regular increment feeding of chain making stock. When, however, the pin 31 is in alignment with the lug 32 the knife edge 27 is locked against the chain stock to prevent feeding at that moment. It is during this halt in feeding of stock that the special chain link is inserted into the press and formed integrally with the regular chain.

The chain being formed and fabricated is shown in detail in Fig. 6. The multiple stage die mounted in the punch press is adapted first to make spaced longitudinally extending score marks 48. The second step in the formation of the chain is to punch a tongue member 49 defined by the spaced score marks 48 downwardly a slight distance. The third step is to cause the tongue 49 to be swung upwardly and the strip of stock to be severed completely as shown at 50. The next step in the chain formation is the downward folding of the tongue 49 about rearwardly disposed cross arm 51 of the link immediately forwardly thereof and thus closing or fastening the links together making a continuous chain of formed links as they emerge from the left-hand side of the machine disposed opposite the feed side as shown at 52. Fig. 6 shows a special link 53 with a laterally extending flange member 54 to which flight members or the like may be attached through an aperture 55. The chain making machine does not fabricate these special links but rather they are made separately inserted into this regular link chain making machine just prior to, or at the time of final assembly or clamping of the tongue member 49 about the adjacent cross end member of the next link in line. The construction of the special link is identical to that of the regular links such as shown at 52 in Fig. 7 wherein the special link 53 is shown in greater detail. The special link is provided with the same upwardly struck tongue 49. When inserted into the press in a position adjoining the completed but not joined standard or regular links it is thereupon moved along with the entire chain, and when the last operation of the multiple stage die closes the tongue 49 about the adjoining link the special link is thus made integral with the entire chain.

The preformed special links are disposed in an inclined magazine 56 and the operator of the machine is required to insert links at the upper or feed end at 57. The links fed into the top end are adapted to push the previously inserted links downwardly toward the discharge end 58 of the magazine 56. A leaf spring 59 is mounted on the magazine 56 at 60 by means of bolts or the like. A spring engaging portion 61 of the spring 59 is adapted to lie on top of the lowermost special link 53 within the magazine 56 and thus restrains the link from being accidentally discharged.

A link injecting carriage in the form of a slide 62 is disposed in a horizontal plane and is mounted for fore and aft sliding movement on a supporting track 63 forming part of the supporting structure 10 of the punch press. The slide 62 is moved inwardly toward the punch press and places a special link in proper position between

5 adjoining links in the fabrication of a steel chain by means of an extension coil spring 64. A guide bracket 65 is carried on the forward face of the punch press frame 10. A rod 66 is adapted to have vertical sliding movement through a vertically disposed hole 67 in the forward end of the guide bracket 65. The upper end of the rod 66 is provided with adjusting nuts 68. The spring 64 is spiraled about the rod 66 between a washer 69 directly beneath the adjusting nuts 68 and the top surface of the bracket 65. The lower end of the rod 66 is fastened to a block member 70 and it should be understood that the spring 64 normally urges the rod 66 and thus the block 70 upwardly. Block 70 carries one end of a laterally extending arm 71 of a bell-crank member 72. A pin 73 joins the block 70 to the arm 71 through a slightly elongated aperture 74 in the arm 71. The bell-crank 72 is pivotally mounted by means of a shaft or pin or the like 75 to a forwardly extending bracket or supporting structure 76 integrally fastened to the supporting structure 10 of the punch press. A second arm 77 of the bell-crank 72 is disposed substantially vertically and extends downwardly. The lower end of the arm 77 has an elongated slot 77a to provide a pivotal attachment with a pin 78 in a block member 79. The block 79 forms part of a superstructure 80 mounted on and integrally attached to the slide member 62 which is adapted to push a special link forwardly into the press.

35 A limit adjusting screw 81 threadedly engages an upwardly extending flange 82 of the track member 63 and by means of a lock nut 83 varies the lateral position of the end 84 of the screw 81. The outer end of the slide member 62 is adapted to abut the end 84 of the screw and thus the outward limit of the slide 62 is controlled. A second screw 85 is threadedly carried in a bracket 86 extending upwardly from the track member 63 and similarly a lock nut 87 is provided for changing the lateral adjustment of the screw. The end abutting portion 88 limits the inward movement of the slide 62. A locking pin 89 is adapted to pass through aligned apertures in the track member 63 and the slide 62 and thus prevents relative or sliding movement of the slide with respect to the track member. The locking pin 89 is vertically reciprocable by means of a solenoid 90 mounted on the framework 10. The solenoid 90 has an upwardly extending armature 91 which is adapted upon energizing of the solenoid coil 90 to be drawn downwardly within the solenoid. An upward extension 92 of the member 91 is attached to the member by means of a cross pin 93. The extension 92 is guided for vertical movement in a shelf-like bracket 94 forming a part of the punch press supporting structure 10. The extension 92 constitutes the abutting or bottom portion of the lock member 89. A coil spring 95 of the extension type is positioned around the extension 92 and between the shelf-like bracket 94 and the under side of a collar 96 fixedly attached to the extension rod 92. The spring 95 thus normally urges the locking pin in an upward or locking position to hold the slide 62 against movement. When the electrical solenoid 90 is energized the member 91 and thus the extension 92 and the locking portion 89 thereof are pulled downwardly, freeing the slide from its locked relationship with the track 63 and permitting the slide to be moved forwardly by action of the extension spring 64.

70 The magazine or slide 56 is shown in detail in Fig. 5. The special links 53 are provided with

spaced tracks or grooves 97 and 98 within which the forward and rearward ends of the chain are adapted to slide. An overhanging bracket member 99 is adapted to confine the link within the tracks 97 and 98 and prevents vertical removal of the links except at the mouth or feed opening 57 and at the discharge end 58. Use of the forwardly and upwardly inclined magazine permits the operator to place one of the special links 53 in position just forwardly of the pushing end of the slide 62. After a special link has been inserted into the fabricated chain the operator inserts another special link into the magazine 56 at 57, thereupon forcing the lowermost link to be discharged at the end 58 of the magazine. This discharged links falls forwardly and downwardly in front of the slide 62 and the other links in the magazine move downwardly and forwardly and are restrained from discharge by reason of the pad 61 of the holding spring 59 engaging the top surface of the lowermost link.

The electrical and mechanical control means for the mechanism of this invention is shown in Fig. 8. The solenoid 90 is shown in this diagram. A source of electromotive force 100 is delivered to a control box 101 by a first pair of lead wires 137 and 152 and a second pair of lead wires 155 and 166 through an opening 102 provided in the top thereof. The control box contains a number of elements including an electrical solenoid 103, a control rack 104, and a plurality of electrical switches 105, 106, 107 and 108. Suitable electric fuses 109 are inserted within the electrical circuits to provide a necessary safety factor.

As best shown in Fig. 2 a projection or stub shaft 110 is affixed to the vertically movable press head 21. This projection moves simultaneously with the movement of the head 21, and by means of a connecting link 111 the projection joins a lever arm 112 extending laterally to one side from the control box 101. The lever arm 112 is pivotally attached by means of a screw or the like 113 to the control box 101. A pawl 114 is pivoted at 115 on the arm 112, and by means of a spring 116 extending from a post 117 on the pawl 114 to a post 118 on the arm 112, the pawl is normally urged about its hinge 115 in a generally clockwise direction as viewed in Fig. 8. A stop 114^a is provided on the control box 101 to limit movement of the pawl 114 by the spring 116. The control rack 104 is provided on its one side thereof with a plurality of ratchet teeth 119 for engagement by the pawl 114. It will thus be seen that upon each punching operation of the punch press the lever arm 112 will be moved about its hinge 113 causing the pawl 114 to engage the ratchet teeth 119 of the control rack 104 causing a downward movement of the rack 104. The rack 104 is provided with an elongated slot 120 extending vertically in substantially the center thereof. Spaced holding screws 121 and 122 pass through the slot 120 and engage the housing of the control box 101. The spaced screws 121 and 122 maintain the rack 104 in vertical position and permit vertical shifting movement of the rack by a sliding of the rack beneath the enlarged heads thereof. A spring 123 anchored by screw means 124 to the control box 101 extends downwardly to attachment at 125 on the upper end of the control rack 104. The spring 123 normally urges the rack 104 to its uppermost position. Downward movement of the rack 104 by reason of the pawl 114 engaging the ratchet teeth 119 is accomplished against the action of the spring 123, and the rack is maintained in its new lowered position by a holding or back locking pawl 75

126. This last-named pawl 126 is pivoted at 127 on the control box housing or plate 101 and is provided with an upward extension which is pivotally attached at 128 on a reduced diameter extension 129 of a solenoid armature 130 forming a part of the electrical solenoid 103. The solenoid 103 thus constitutes a recycling solenoid for the apparatus. The solenoid armature 130 is provided with a vertically disposed head portion 131 engageable by a spring 132 which is coiled about a screw post 133 and is prevented free rotation about the post 133 by engagement with a screw member 134. The screw members 133 and 134 are both mounted on the control box housing 101. The spring 132 is arranged and constructed to normally urge the armature 130 outwardly and thus cause the pawl 126 to remain in engagement with the ratchet teeth 119 on the control rack 104 preventing back up of the rack following downward movement thereof by the pawl 114. As stated in the objects above, the rack 104 controls the spacing of the special links in the chain being fabricated. The amount of throw of the lever arm 112 and thus the amount of downward movement of the rack 104 by the pawl 114 can be varied by positioning the pawl 114 at various spaced positions along the arm 112. The device is shown so that upon each movement of the press plunger 21 the rack 104 will be moved downwardly a distance equal to one notch or tooth on the ratchet face 119.

Continued movement of the rack 104 downwardly by the procedure just described and the maintenance of the rack in its newly lowered position by the pawl 126 will continue until the lower edge 135 strikes contact member 136 adapted to control the electrical switch 105 by causing an inward movement of a push button 105^a on the inner face thereof. It is obvious from the construction of this mechanism that the rack 104 will cause a spreading of the contact arm 136 and thus complete the electrical circuit through the switch 105. One of the E. M. F. lead wires designated by the numeral 137 passes through the fuse box 109 to connection at 138 with a circuit wire 139 joining the electrical switch 105 at 140. The other side of the switch 105 designated by the numeral 141 receives a wire 142 which travels through the fuse box 109 outwardly through the wire 143 and thereupon joins the solenoid 90 at 144. The other connecting post 145 of the solenoid 90 receives an electrical wire 149 which returns through the fuse box 109 and joins a circuit wire 150 which is diverted at 151 for rerouting through the fuse box 109 and thereupon out to a second lead wire 152 of the source of E. M. F. It will thus be seen that the electrical circuit between the switch 105 and the solenoid 90 is completed to the source of E. M. F. The solenoid 90 is thus energized upon the closing of the electrical switch 105. Thus as the control rack 104 strikes the contact arm 136 the solenoid 90 is energized causing a retracting of the locking pin 89 and permitting the spring 64 to push or shove a special link 53 into position in the chain being fabricated. The completed fabricated chain thus contains special links at regularly spaced intervals.

The control rack 104 after effecting operation of the contact arm 136 engages a contact arm 153, closing the electrical switch 106 by compression of a push button 154. A third lead wire 155 at the source of E. M. F. delivers electrical energy through a wire 156 to a juncture 157 with

an electrical wire 158. The wire 158 continues the circuit to a juncture 159 with a wire 160 and thereafter carries the electricity to a connection 161 on the switch 106. A connector 162 on the switch 106 is joined by a wire 163 which passes upwardly to a juncture 164 with a wire 165 which feeds out to a fourth lead wire 166 at the entrance of electrical energy designated by the numeral 100. The circuit to the switch 106 is thus completed to the power source. A wire 167 extends from the juncture 159 to one of the connector points 168 on the solenoid 103. The other side of the solenoid coil designated by connector point 169 is joined to an electrical carrying wire 170 to the junction 151 adjacent the fuse box 109 and thereupon passes through the fuse box outwardly through a wire 171 to the E. M. F. line 152. It is apparent that as the switch 106 is closed permitting passage of electrical current the solenoid 103 is energized causing the armature 130 to be moved forwardly and the pawl 126 to be swung out of engagement with the toothed rack 119 permitting the spring 123 to pull the entire control rack 104 upwardly until it strikes the stop 172 mounted on the control box housing 101.

A projection 173 extending laterally from the control rack 104 adjacent the top thereof engages and swingingly moves a contact arm 174 which causes depression of the push button 175 of the switch 107. It should be understood that all of the switches 106, 107 and 108 may be of the micro-switch type to insure accurate operation of this device. Switch connector points 176 and 177 are carried directly by electrical wires to the E. M. F. source of supply. A wire 178 is attached to the connector 176 and runs into the wire 165 which joins the source of E. M. F. at 166. A wire 179 joins the connector 177 and runs to the junction 138 whereupon it is delivered to and through the fuse box 109 and continues through a wire 180 to the E. M. F. lead 137. Thus as the micro-switch 107 is opened upon depression of the push button 175 the solenoid 103 is deenergized permitting the armature 130 to be retracted by the coil spring 132 and thus also permitting engagement of the ratchet teeth 119 by the pawl 126.

The micro-switch 108 is closed by the cross head 131 of the solenoid armature 130 by the engagement of a contact arm 178, which as shown in Fig. 8 is in holding engagement with a push button 179 of this micro-switch. The switch 108 is provided with connecting points 180 and 181. The connecting point 180 is joined by a wire 182 which in turn joins the wire 165 completing the circuit to the E. M. F. source 166. The connecting point 181 is joined by a wire 183 which passes outwardly to connection with the electrical conductor 156 which feeds out to the E. M. F. lead 155.

An irregularly shaped plate 184 carries the micro-switches 105 and 106 and depends from a supporting bracket 185 held in the control box housing 101 by bolt members 186 and 187. A plurality of holes 188 is provided in the bracket plate member 185, and a screw 189 projecting outwardly from the irregularly shaped plate 184 is adapted to pass through any desired one of the apertures 188. A wing nut 190 engages the screw 189 and may be drawn up to lock the plate 184 with the bracket 185. It will thus be seen that the micro-switches 105 and 106 can be raised or lowered as desired and thus control the spacing of the special links 153 in the finished

fabricated chain. If, for example, the switches 105 and 106 are moved downwardly the control rack 104 will necessarily move further downwardly before actuating the switches and thus greater intervals of spacing will be provided in the chain between the special links 153.

Operation of the device

The punch press is started and the strip of metal stock is automatically fed in short increments into the position beneath the multiple stage die whereupon the chain is formed in the manner indicated in Fig. 6. When the control mechanism located at the rear of the machine, and shown in detail in Fig. 8, acts to energize the controlling electrical solenoid 90, the feed of the material is temporarily halted. The operator has previously inserted one of the special links in the top of the magazine 56 to cause a discharge of the lowermost link in the magazine down into position in front of the slide 62. The forward movement of the slide positions this link into the space beneath the multiple stage die which was left vacant by the fact that feed of new material was temporarily halted. It addition to the actuation of the solenoid 90 his same electrical circuit is arranged and constructed to energize a warning light or signal which indicates to the operator that the intersperser is to operate on the next stroke of the press and that it is time to insert a new special link into the receiving magazine 56. The warning light is designated as numeral 146 and is attached in parallel to the circuit containing the solenoid 90 by lead wires 147 and 148 to the circuit wires 143 and 149.

The control rack 104 moves downwardly one notch or tooth 119 for each stroke of the press. After the selected number of strokes, determined by the vertical position of the plate 104 which carries the micro-switches 105 and 106, the rack strikes the contact arm of the switch 105 to effect a completion of the electrical circuit to the solenoids 41 and 90. The control rack 104 thereafter engages the contact arm 153 of the micro-switch 106 which completes the electrical circuit to the solenoid 103 which causes recycling of the apparatus by energizing that solenoid and causing a forward movement of the armature 130 and a simultaneous disengagement of the pawl 126 from the ratchet teeth 119 permitting the rack 104 to move bodily to its uppermost position as shown in Fig. 8. The stop 172 limits upward movement of the rack by the spring 123. The projection 173 on the control rack actuates the micro-switch 107 by depressing the contact arm 174. The micro-switch 107 is arranged and constructed to disconnect electrical energy from the solenoid 103, and thus the pawl 126 is permitted to be pulled back into engagement with the ratchet teeth 119 by the spring 132 and the cycle of operation may thus be repeated. The micro-switch 108 is in the same circuit with the micro-switch 106, and in order to complete the energizing of the solenoid 103 it is necessary that the armature 130 be in its retracted position so that the cross head 131 will depress the contact arm 178 of the micro-switch 108 in the manner shown in Fig. 8.

It is believed that herein is provided a unique apparatus for the fabrication of steel chain having incorporated therein specially-shaped links at regular intervals throughout the length thereof, and it is apparent that numerous details of

construction may be varied throughout a wide range without departing from the principles disclosed herein, and I therefore do not propose limiting the patent granted hereon otherwise than as necessitated by the appended claims.

What is claimed is:

1. In a chain making apparatus having a punch press with a reciprocating head, a multiple stage chain making die for said press, a stock feeding device operable in response to operation of said punch press, means for intermittently rendering said feeding device ineffective to feed stock, means on said apparatus for inserting a special chain link into the formation of the chain at a time concurrently with the halting of feeding of the stock, said means for inserting a special chain link including an electrical solenoid, means for intermittently energizing said solenoid, said means for intermittently energizing the solenoid including a source of electrical energy, electrical switch means, electrical wiring joining the source of electrical energy with the solenoid and the switch means, mechanical means for actuating said electrical switch means, said mechanical means including a toothed rack arranged and constructed on said apparatus for sliding movement with respect to the apparatus, an arm pivotally mounted on said apparatus and connected to the reciprocating head of the punch press to impart arcuate swinging movement to the arm upon each reciprocal movement of the head, a pawl mounted on said arm and adapted to engage and move the toothed rack in regular increments, a first part of the switch means positioned in the path of the toothed rack in such a manner that the rack in its desired moved position acts to close the switch means and complete the circuit to the solenoid and thus energize the solenoid, a holding pawl pivotally mounted on said apparatus, spring means normally urging said holding pawl into engagement with the toothed rack and arranged and constructed to regularly permit movement of the rack only in one direction, a second solenoid mounted on said apparatus and having a movable portion thereof connected to said holding pawl, a spring normally urging said toothed rack away from said switch means, and

a second part of said switch means located close to the first part of said switch means and arranged to be actuated by said toothed rack subsequent to the actuation of the first part of said switch means, and circuit wiring arranged to include the source of electrical energy, the second part of said switch means, and the second solenoid, whereby actuation of the second part of the switch means completes the electrical circuit to and energizes the second solenoid to thus release the holding pawl and permit the toothed rack to be moved by the spring and resume its original position for the resumption of another cycle of operation.

15 2. An apparatus as set forth in claim 1 in which a third part of said switch means is located at the opposite end of the toothed rack from the first and second switch means parts, said third part of said switch means adapted to be opened by said toothed rack when the rack is in its starting position, and said last-named third part of the switch means is positioned in the circuit with the second solenoid whereby just as soon as the rack is returned to its starting position the electrical energy to the second solenoid is withdrawn permitting the holding pawl to reengage the toothed rack.

20 3. An apparatus as set forth in claim 2 in which the first and second switch means parts are mounted on a plate, and means for adjustably fastening said plate to said apparatus whereby the spacing between the special links in the finished chain may be conveniently controlled by shifting said solenoid holding plate toward or 25 away from said toothed rack.

CLARENCE E. VANDENBERG.
